HAIR CURLER

Sydor Solop, Woodside, N. Y.

Application February 2, 1950, Serial No. 141,897

2 Claims. (Cl. 132—41)

1

My present invention relates to improvements in hair curlers and more particularly to hair curlers having a mandrel swingably mounted within a retainer unit adapted to snap latch to the free end of the mandrel after the strands of hair to be curled have been wound on the mandrel.

Heretofore hair curlers of the usual pivotally connected mandrel and the retainer type have been formed from at least three members. That is, the mandrel, the retainer and a hinge pin for pivotally connecting the mandrel and retainer together. This extra hinge pin is a source of bother as it is required to be inserted separately to join the mandrel and retainer units and makes the manufacture of the product too expensive as it slows down production.

The principal object of this invention is to provide a two piece hair curler with a complete mandrel unit and a complete retainer unit requiring no separate pivot pins.

Another object is to provide for mass production of mandrels and retainers as completely formed individual units adapted to be quickly snapped together to form a complete hair curler assembly.

The above, other objects and advantages of my invention will more fully appear hereinafter from a consideration of the detailed description which follows, taken together with the accompanying drawings, wherein two embodiments are illustrated.

Figure 1 is a perspective assembled view of one form of my novel two part hair curler in assembled relation and latched position and showing it unassembled in dotted line.

Fig. 2 is a pulled apart fragmentary perspective view of the integral interfitting pivotal connections between the unitary parts of the first form of my invention.

Fig. 3 is a pulled apart fragmentary perspective view of the integrally made interfitting pivotal connections between the unitary parts of a second form of my invention.

Fig. 4 is a cross section view of form one taken along the line 4—4 of Figure 1.

Fig. 5 is an assembled cross section view of the integral pivotal connections between the mandrel and retainer members of the second form of my invention.

Referring to the drawing in detail and first with respect to the form illustrated in Figures 1, 2 and 4, there is an elongated curler mandrel 10 formed with axially extending square edges 11. Between the edges 11 the mandrel 10 is formed

with elongated grooves 12. The edges 11 and grooves 12 serve to assist in keeping wound hair strands on the mandrel from slipping.

The mandrel 10 is notched on its free end 13 so as to latch in the head 15 of the retainer member or unit 14. The latch member 16 of the head 15 is a transverse V-lug, which seats in the notched mandrel end 13 when it swings and snaps closed on the novel pivotal unitary connections of my present invention.

These new pivot connections may be formed by molding, forging, carving or casting from the material of their respective parts. The forming process will depend upon the material used, which is preferably of synthetic plastic compounds, such as acrylic resins or the like. For example, the retainer unit 14 is bowed and yieldably resilient. It is formed opposite to latch head 15 with a pair of apertured spaced apart ears 18 and 19. The ears 18 and 19 project from the inner curve or concave side of the bowed retainer 14 and the apertures 20 and 21 of each ear are axially aligned with each other to receive the pivotal connection of the mandrel 10.

The mandrel 10 is formed opposite its notched end 13 with an axially offset single ear 22 similar in shape to the spaced apart apertured ears 18 and 19. Projecting from each side of the ear 22 are axially aligned lugs 23 and 24, which are respectively adapted to snap into one of the aligned apertures 20 and 21 of the ears 18 and 19, respectively.

The joining together of the ears 18, 19 and 22 by snapping of the lugs into the apertures may be facilitated by slightly slanting the surface of the ears around each aperture and by slightly rounding the ends of the lugs 23 and 24.

A knurled knob 28 may be formed from the head 15 of the retainer unit 14 to provide for turning the mandrel 10 when the units are swung apart in aligned hair curling position.

The second form of my invention illustrated in Figures 3 and 5 includes the same mandrel structure 10, 11, 12 and 13 and the same bowed retainer structure 14, 15 and 16. However, the ear structures are somewhat reversed and accordingly are given new numerals. For example, the mandrel 10 has a single ear 30 formed with an opening or aperture 31 and the resilient bowed retainer unit 14 has a pair of spaced apart ears 32 and 33 each formed with integral lugs 34 and 35 projecting in axial alignment toward each other between their respective ears 32 and 33.

The arrangement of the second form permits rapid snap assembly of the mandrel and retainer

units and provides opposed flat bearing surfaces between the inner sides of each ear and the flat sides of the single mandrel ear 30. Also with this arrangement there are no exterior recesses or projections on the ears 32 and 33 and the exterior surface of this part of the curlers is entirely smooth. It is desirable to eliminate all recesses and projections on this part of the curler because recesses collect foreign matter and must be cleaned out and projections often become tangled with stray hair strands, thereby interfering with the curler's efficiency.

Without further description it is believed that my invention will now be clearly understandable and the advantages and improvements thereof over the prior art will be apparent. While I have described and illustrated only two embodiments of my invention in detail, it is to be expressly understood that other combinations, modifications and arrangements of the parts which will now probably occur to others skilled in the art are to be considered a part hereof. To determine the scope of my invention reference should be had to the appended claims.

What is claimed is:

1. A two-piece hair curler comprising a resilient bowed retainer unit formed with spaced apart ears at one end and a latch head having a transverse V-lug at the other end, a pair of axially spaced lugs formed from each ear between the same, and a mandrel unit having its free end notched to engage the said transverse V-lug on the latch head, said mandrel being formed with an apertured ear, the aperture being engaged by the said lugs to pivotally connect the said units, and an axially extending knurled handle formed from the latch head for revolving the mandrel to wind a curl thereon, said mandrel

being rectangular in cross section and formed with longitudinal grooves in each side, to thereby resist uncurling of a curl on the mandrel.

2. A two-piece hair curler comprising a resilient bowed retainer unit formed with spaced apart ears at one end and a latch head having a transverse V-lug at the other end, a pair of axially spaced lugs formed from each ear between the same, and a mandrel unit having its free end formed with a V-notch to engage the said V-lug on the latch head, said mandrel being formed with an apertured ear, the aperture being engaged by the said lugs to pivotally connect the said units, and an axially extending knurled handle formed from the latch head for revolving the mandrel to wind a curl thereon, each of the edges around each aperture being tapered inwardly to facilitate the assembly between the pivotal connections formed by the said ears and lugs.
